UNITED STATES PATENT OFFICE.

JACOB F. MEHREN, OF CHICAGO, ILLINOIS.

SIGNAL-BOX.

1,264,671.

Specification of Letters Patent. Patented Apr. 30, 1918.

Application filed December 14, 1914. Serial No. 877,101.

To all whom it may concern:

Be it known that I, JACOB F. MEHREN, a citizen of the United States, residing at Chicago, in the county of Cook and State of Illinois, have invented a new and useful Improvement in Signal-Boxes, of which the following is a specification.

My invention relates to an improvement in the class of signal boxes, or signal stations as they are also termed, which are commonly installed in places readily accessible to the public to enable fire and police alarms to be sent in; and it relates more particularly to the improvement of such signal boxes which are equipped with local alarm-sounding or warning devices. The primary purpose of the last-named equipment, which is automatic in its operation, is to attract the attention of passers-by, or of others in the neighborhood of the box or station, to the end of leading to the observation of persons turning in alarms and enabling their apprehension if the alarms are found to be false and prompted by mischief or malice. In the present instance, this warning alarm may be of any suitable type of noise-producing apparatus and provided in or on the signal box or at any nearby or more or less distant place, where it may be heard when set off by actually swinging open the outer door of the box to gain access to the signal-sending mechanism for starting it.

The primary object of my improvement is, while tending to deter misuse of the signal box in the manner stated, to facilitate sending alarms by the general public by omitting all features tending to obstruct or mislead those who are inexperienced in operating such boxes, besides dispensing with locks and keys, or other securing devices, and glass requiring to be smashed for gaining access to the mechanism for operating it, thereby avoiding confusion and possibly disastrous delay in sending alarm signals.

In the accompanying drawings, Figure 1 is a view in front elevation, with a part of the outer hinged door broken away, to disclose certain details, of a signal box equipped with my invention; Fig. 2 is a similar view of the same with the outer door open and shown broken; Fig. 3 is a view partly in section on line 3, Fig. 1 and enlarged, and partly diagrammatic in its showing of the local warning mechanism in a local-battery circuit operatively combined with the alarm

sending or transmitting mechanism included in the main-line-circuit; Fig. 4 is a similar view but showing both the alarm-sending mechanism and the local warning mechanism in the main-line-circuit, and Fig. 5 is a diagram showing a modification of the circuits of Fig. 3.

The box 7, or outer case, of the shape illustrated or of other suitable shape, is provided with an outer hinged door 8 carrying a knob 9, or handle, on the outer end of a shaft 10 journaled in the door and carrying on its inner end a latch 11 to engage with a lip 12, or keeper, formed at a slot 13^a in the sunken door-stop 13 about the open face of the case. A spring 14 on the inner face of the door tends to hold the latch in its keeper to secure the door in closed position. As is usual in boxes of the present kind, an inner case 15 is secured and housed in the outer case and is also provided with a hinged door 16, closed against access by the public to the mechanism in the inner case, involving the alarm-transmitting mechanism and may be, also, as intended in the present instance, the local warning mechanism, though the latter may be outside of or at a distance from the box without departure from my invention. In the door 16, near its left-hand lower corner, is shown a hole 16^a to admit, for the purpose hereinafter explained, a pin 17 projecting from the inner face of the outer door. The alarm-transmitting mechanism is preferably that in common use in fire-alarm signal-boxes and is too well known to require detailed illustration and description herein. It comprises the usual toothed signal-wheel 18 on a suitably journaled shaft 19 carrying loosely a pinion, indicated at 20, rotatable in one direction by a pawl and ratchet device (not shown). The door 16 contains an arc-shaped slot 21, through which projects a handle 22 on the end of a crank-arm 23 extending at the inner side of the door from a rock-shaft 24. An arm 25 extends from this shaft and terminates in a segmental rack 26 meshing with the pinion 20, the arm turning in one direction against the resistance of a spring 27 coiled about the shaft and having one end fastened at 27^a and its other end to the arm, which is retracted by the recoil of the spring.

In the inner casing is supported an electric switch 28, of the preferred construction illustrated, having as its parts a base 29

of insulating material (hard rubber) carrying contact members 30 and 31, and a metal loop-forming bar 32 from which spring contact-fingers 30^a and 31^a extend and converge 5 toward their forward ends to opposite sides of a spring-retracted plunger-rod 33 reciprocably confined in the loop and provided on its outer end with a knob 34 to be engaged by the pin 17. At 35 is represented 10 an electric-bell apparatus as the preferred device for the local warning signal, this apparatus being of the ordinary make-and-break type, as illustrated in Fig. 3. The electromagnet of this apparatus is included 15 in the circuit of a local battery, indicated at 35^a, this circuit having one side of the battery connected with the contact-member 30 and the other, through the bell, with the contact-member 31. The main-line circuit 20 36 has one wire connected at 37 with a spring-retracted pivotal contact-finger 38 supported to make and break the circuit 36 at a contact-member 39 therein by the vibrating action, against its curved insulated 25 end, of the toothed wheel 18. One side of the local-battery circuit has two branches connected with it at 40, one branch leading directly to the contact-member 30 and the other branch being connected at 41 with 30 the strip 32; and this branch contains a spring contact-finger 42 and a contact-member 43 crossed by the contact-finger, which is held out of contact with the member 43, against a stop 44, by the rack 26, normally 35 bearing at its insulated end against the finger.

To operate the local-alarm the knob 9 is turned to unlatch the door 8, pulling open 40 of which withdraws the pin 17 and permits the plunger 33 to be retracted by its spring until stopped by the head 34 striking the door 16. This withdrawal of the plunger frees the finger 30^a to permit it to snap against the contact-member 30; but the 45 plunger continues to hold the finger 31^a against the contact-member 31, because the last-named finger is shorter than the finger 30^a and bears against the plunger at a point behind that at which the adjacent end of 50 the longer finger bears against it. The battery-circuit is thus closed and the bell sounds the local alarm, thereby attracting the attention of passers-by, or of those in the neighborhood, and affording opportunity 55 for apprehension of the operator if his act proves to be mischievous. If, however, the operation is *bona fide* and the alarm-signal is to be sent, the person, seeing the handle 22, pulls it downwardly. This 60 withdraws the rack 26 from the finger 42, thereby closing the local-battery circuit also at 43. Upon releasing the handle thus pulled down, the spring 27 returns the rack to its normal position, in reaching which it 65 causes rotation of the toothed wheel 20 to

vibrate the arm 38 and make and break the main-line circuit at 39 for sending the alarm-signal over the line. In the return of the rack it encounters the finger 42 and separates it from the terminal 43. In the meantime, the outer door being open, the local-battery circuit remains closed, both at 30 and 43, and the warning signal continues. If, while the alarm-signal is working, the outer door 8 is shut to cause the 75 pin 17 to push the plunger 33 inwardly, it will break the local-battery circuit at 30, but the bell will continue to ring until it is also broken at 43 by the rack, in gaining its normal position, forcing the finger 42 away. 80

As will be seen on inspection of Fig. 4, which shows the circuit and mechanism in normal condition, as in Fig. 3, the bell 35 is not in a local-battery circuit but is in the main-line-circuit. In this condition, the 85 current, which is always on the main line, passes through the switch-device 28 and fingers 42 and 38, to the return-side of the line at 39, thus through a shunt around the bell. When, however, on pulling open the 90 outer door, the shunt-circuit is broken at 30 by resultant retraction of the plunger 33, and afterward at 44 by pulling down the 95 operating handle 22, the main-line current flows through the bell and sounds it; and it continues to ring while the rack is working the alarm-mechanism. The bell shown in this instance differs from that represented in Fig. 3 in being not of the make-and-break type, but of the type in which the 100 electromagnet is cut, by the vibrations of the clapper-armature, alternately in and out of circuit.

In cases where it is desired to open the inner door 16, as for example, when the fire 105 marshal wishes to communicate with the central office (for which purpose the inner case is always equipped with telegraphic apparatus, though none is shown in the drawings), he would be disturbed by the 110 noise of the local alarm if that were to continue. However, on opening the inner door, the plunger, in the arrangements illustrated both in Fig. 3 and in Fig. 4, is retracted by 115 its spring far enough to permit, in the one instance, the finger 31^a to separate from the contact-member 31, and in the other instance, the finger 31^a to spring against the contact-member 31, thereby cutting out the bell in each instance. That is to say, with 120 regard to the showing in Fig. 3, the local-battery circuit is broken at 31, and with regard to the showing in Fig. 4, a shunt is thrown around the bell by the closure at 31.

The inner door 16 is intended to remain 125 closed to the public, but may nevertheless be opened without difficulty, not being ordinarily locked but merely latched, so that any one having authority may readily gain access to the mechanism in the inner case by 130

opening both doors. As has already been explained with reference to Figs. 3 and 4, however, opening of the inner door while the alarm-signal is operating, stops the ringing of the bell 35. A mischievous person becoming aware of that might desire to use the knowledge to avoid attracting much if any attention after operating the alarm-signal to send in a false alarm. To prevent this, 5 the circuits may be arranged as illustrated in Fig. 5 to include a local-battery circuit, as in Fig. 3. In this arrangement, on opening the outer door to permit retraction of the plunger, the local-battery circuit is closed by the finger 30^a at 30, and on pulling down 10 the rack, the finger 42 also closes it at 43. On opening the inner door 16, however, the resultant further retraction of the plunger will permit the finger 31^a to open the local-battery circuit at 31, but it will remain 15 closed at 43 until opened by the return of the rack to normal position and thus, in the meantime, cause the ringing of the bell to continue. An inspector, who opens the inner door to gain access to the interior of the box for testing the alarm-mechanism may avoid 20 being disturbed by the continued sounding of the local alarm by depressing a key 45, shown to be provided in Fig. 5, away from a contact-member 44 in the branch of the local-battery circuit containing the finger 42, thereby opening that branch and cutting out 25 the bell.

While my invention is shown and described as being embodied in electrical mechanism, it is not intended to be limited thereto since the principles thereof are susceptible 30 of mechanical embodiment; nor do I intend by illustrating specific or preferred details 35 for disclosing my invention, to be limited thereto, since these may, without departure therefrom, be variously modified.

What I claim as new and desire to secure by Letters Patent is:—

- 45 1. In a signal-box of the character described, a case provided with a door, lever-operated signal-transmitting mechanism supported in said case and accessible by opening said door, automatic local-sounding mechanism, and means controlled by said signal-transmitting mechanism for releasing into operation said sounding mechanism upon operating said lever to start the action of said signal-transmitting mechanism.
- 50 2. In a signal-box of the character described, a case provided with a door, signal-transmitting mechanism supported in said case and accessible by opening said door, automatic local-sounding mechanism, means releasing into operation said sounding mechanism by opening said door, and means continuing said operation of the sounding mechanism on starting into action said signal-transmitting mechanism and while the latter is in action after closing said door.

3. In a signal-box of the character described, an outer case provided with a door, an inner case provided with a door, signal-transmitting mechanism supported in the inner case, automatic local-sounding mechanism, and means releasing into operation said sounding mechanism on opening the outer door and arresting such operation on opening the inner door. 70

4. In a signal-box of the character described, a case provided with a door, an electric main-line circuit, lever-operated signal-transmitting mechanism in said circuit supported in said case and accessible by opening said door, a local electric circuit, electric sounding apparatus and a generator in said local circuit, and an automatic switch coöperating with said signal-transmitting mechanism to open said local circuit while said transmitting mechanism is in its inactive condition and to close said local circuit upon operation of said lever to start the action of said transmitting mechanism. 75

5. In a signal-box of the character described, a case provided with a door, an electric main-line circuit, signal-transmitting mechanism in said circuit supported in said case and accessible by opening said door, a local electric circuit, electric sounding apparatus and a generator in said local circuit, an automatic switch coöperating with said door to close said local circuit on opening said door, and an automatic switch coöperating with said signal-transmitting mechanism to continue the closed condition of said local circuit upon starting into action said transmitting mechanism and while the latter is in action after closing said door. 90

6. In a signal-box of the character described, an outer case provided with a door, an inner case provided with a door, an electric main-line circuit, signal-transmitting mechanism in said circuit supported in the inner case, a local electric circuit, electric sounding apparatus and a generator in said local circuit, and an automatic switch coöperating with the outer door to close said local circuit by opening said outer door and with the inner door to open said local circuit by opening said inner door. 105

7. In a signal-box of the character described, an outer case provided with a door, an inner case, an electric main-line circuit, signal-transmitting mechanism in said circuit, supported in the inner case and having an operating handle accessible by opening said door, said mechanism including a spring-retracted segmental rack and a pinion, a local electric circuit opened by movement of said rack in one direction and closed by movement thereof in the opposite direction, electric sounding apparatus including a switch in said local circuit, and a projection on said door coöperating with the switch to open thereat said local circuit in 110 120 125 130

the closed condition of the door and there close the same by withdrawing the projection in opening the door.

8. In a signal-box of the character described, an outer case provided with a door, an inner case, an electric main-line circuit, signal-transmitting mechanism in said circuit, supported in the inner case and having an operating handle accessible by opening 10 said door, said mechanism including a spring-retracted segmental rack and a pinion, a two-branch local electric circuit including a circuit opening and closing finger in one branch operated by said rack, electric 15 sounding apparatus including a switch in the other branch of said local circuit, and a projection on said door coöperating with the switch to open at the latter said local circuit in the closed condition of the door and 20 there close the same by withdrawing the projection by opening the door.

9. In a signal-box of the character described, an outer case provided with a door, an inner case, an electric main-line circuit, 25 signal-transmitting mechanism in said circuit, supported in the inner case and having an operating handle accessible by opening said door, said mechanism including a spring-retracted segmental rack and a pinion, a two-branch local electric circuit including a key and a circuit opening and closing finger in one branch, operated by 30 said rack, electric sounding apparatus including a switch in the other branch of said local circuit, and a projection on said door coöperating with the switch to open at the latter said local circuit in the closed condition of the door and there close the same by withdrawing the projection by opening 40 the door.

10. In a signal-box of the character described, an outer case provided with a door, an inner case provided with a door, an electric main-line circuit, signal-transmitting

mechanism in said circuit, supported in the 45 inner case and having an operating handle projecting through the inner door to be accessible on opening the outer door, a two-branch local electric circuit including a circuit opening and closing finger in one branch 50 operated by said signal-transmitting mechanism, electric sounding apparatus in the other branch of the local circuit, including a switch provided with a spring-retracted plunger, and a pin on the outer door 55 projecting, in the closed condition of the latter, through the inner door against the adjacent end of said plunger, for the purpose set forth.

11. In a signal-box of the character described, an outer case and an inner case each provided with a door, an electric main-line circuit, signal-transmitting mechanism in said circuit, supported in the inner case and having an operating handle projecting 60 through the inner door to be accessible on opening the outer door, a two-branch local electric circuit including a circuit opening and closing finger in one branch operated by working said signal-transmitting mechanism, electric sounding apparatus in the other branch of the local circuit, a switch 65 in said last-named branch comprising a base, a pair of contact-members, a plunger-guiding block having extending from it across 70 said members a pair of relatively longer and shorter contact fingers converging toward their inner ends, and a spring-pressed plunger reciprocably supported on said block to extend between said converging fingers, and 75 a pin on the outer door projecting, in the closed condition of the latter, through the inner door against the adjacent end of said plunger, for the purpose set forth.

JACOB F. MEHREN.
